UNITED STATES PATENT OFFICE

THOMAS L. PARKER, OF CHICAGO, ILLINOIS
ELECTRIC SWITCH

Application filed April 24, 1929. Serial No. 357,752.

My invention relates to electric switches and more particularly it relates to switches adapted for mounting on the handle or lever of a manually controlled device. The device 5 of my invention is particularly adapted for use with electrically actuated manually propelled devices, such for example, as vacuum cleaners and other similar instrumentalities and it is also adapted for use with all sorts 10 of portable or stationary electrically operated devices, wherein it is desirable to have a switch conveniently mounted on the instrument or device which is being operated.

One of the objects of the invention is the 15 provision of improved means adapted to compensate for wearing or abrasion of the contact members thereby insuring complete contact connections when the switch is closed, regardless of the amount of services to which 20 the device has been subjected.

Another object is the provision of a mounting 25 for the conductors and contact which provides for their complete insulation for all positions of the same and eliminates the possibility of any other portion of the device becoming charged.

The mechanism is assembled and mounted 30 as a unit, the mounting being so arranged that upon disassembling the switch the mechanism remains intact as a unit and a further object of the invention is the provision of an improved mounting and assembly of the switch actuating mechanism.

Another object of the invention is the provision 35 of a switch of the kind described which is simple, compact, easily manipulated and can be manufactured at low cost.

Many other objects and advantages of the 40 construction herein shown and described will be obvious to those skilled in the art from the disclosure herein given.

To this end my invention consists in the 45 novel construction, arrangement and combination of parts herein shown and described, and more particularly pointed out in the claims.

In the drawing, wherein like reference 50 characters indicate like or corresponding parts:

Fig. 1 is an end elevation view of the device;

Fig. 2 is a side elevational view;

Fig. 3 is a view along the line 3—3 of Fig. 1 drawn to a larger scale; 55

Fig. 4 is a view along the line 4—4 of Fig. 3; and

Fig. 5 is a view along the line 5—5 of Fig. 3.

Referring now more particularly to the drawing, the numeral 10 generally designates 60 a face plate having a U-shaped cross-section which, together with a plurality of sheets of insulating material 12 make up the main body of the switch. The insulating material is arranged in a plurality of sheets for ease 65 in assembling and may be of any desired material, such as bakelite or any suitable fibrous material, which has insulating qualities. The sheets 12 are fastened together and to the face plate 10 by a plurality of rivets 15, the face 70 plate 10 being for this purpose provided with a pair of upper end projections 14 between which the sheets 12 are positioned.

The sheets 12 provide an insulated mounting 75 for binding head screws 13. The screws 13 are mounted on binding posts 16. The binding posts 16 are each fastened to an adjacent sheet 12 by oppositely positioned rivets 17, the middle one of the sheets 12 serving 80 to insulate the rivets from each other. Contact brushes 9 are positioned between the binding posts 16 and the adjacent sheets 12. A rocker arm, generally designated by the numeral 11 is pivotally mounted upon a pin 19 which extends through the outstanding 85 side portions of the face plate 10. The sheets 12 are concave towards the plate 10 and together with the plate provide a housing in which the rocker arm 11 may swing to open 90 and to close the circuit.

An insert 26 projects through a slot 28, formed for that purpose in the face plate 10, the slot being of sufficient length to permit the insert lever to be rotated as desired about the pin 19 upon which it is mounted. A 95 knob 27 is provided on the outer end of the lever 26 to permit easy actuation of the lever in controlling the rocker arm 11 which is pivotally mounted on the pin 19.

The rocker arm 11 comprises a U-shaped 100

plate 21 having its open end rotatably mounted on the pin 19. A flat rivet or pin 22 is mounted on the closed end of the plate 21 and is provided with an enlarged head cut 5 away sufficiently to act as a guide pin for one end of a compression spring 23. A pair of shouldered insulating washers 24 are mounted on the rivet 22. The rivet 22 is made flat to prevent its rotation on its mounting as well as to prevent the washers 24 from rotating about their mounting on the rivet. The outer end of the rivet 22 is spread and thereby holds the washers 24 fixed against movement longitudinally of the rivet. A 10 contact ring 25 is mounted on the washers 24, completely filling the space between the shouldered ends of the washers. The washers 24 provide a mounting which completely insulates the ring 25 from the remaining portion of the rocker arm 11. The outer diameter of the ring 25 is preferably slightly greater than that of the shouldered portions 15 of the washers 24.

The inner end of the lever 26 forms a toggle 25 mechanism comprising oppositely positioned stop fingers 29 and a centrally positioned stem 30. A socket 31 in the mid portion of the stem 30 provides a fastening means for one end of the compression spring 23. The 30 projecting head of the rivet 22 serves as a guide to hold the other end of the spring 23 in place.

The full line position of the rocker arm 11 and of the insert lever 26 corresponds to the 35 open position of the mechanism. It will be observed that the spring 23 tends to hold the arm 11 in the full line position. The circuit is closed by pushing downwardly on the insert lever 26. The spring 23 resists the 40 downward movement of the lever 26 until the lever reaches its neutral position of alignment with the rocker arm 11. Further movement of the lever 26 will be accelerated by the resiliency of the spring 23 and the rocker arm 45 11 is thereby impulsively moved from its full line position to its dotted line position wherein the circuit is closed.

The projecting ends of the contact brushes 9 are formed to project inwardly. In moving 50 to its closed position, the rocker arm 11 brings the ring 25 into engagement with the contact brushes 9 which are positioned in its path. The contact brushes 9 have their projecting ends conforming to the curvature 55 of the ring 25 so as to insure surface contact therewith. The extreme ends of the contact brushes 9 have a slight outward curvature which forms a guide for the ring 25 as the ring moves into engagement with the resilient 60 contact brushes. The contact brushes 9 are so spaced as to be spread slightly when the ring 25 is positioned therebetween. The construction and arrangement of the contact brushes 9 thereby compensate for any wear 65 of the contacting parts and insure their ef-

fective cooperation with the ring 25 during the entire life of the device. The dotted line shows the position of the lever 26 and the rocker arm 11 when the circuit is closed. The circuit is opened by pushing the lever 70 26 upwardly and the resulting actuations of the toggle means mounted on the inner end of the lever 26 is opposite to and similar to the movements described for moving the rocker arm 11 from its full line to its dotted 75 line position. The rocker arm 11 retains its dotted line position with the ring 25 between the contact brushes 9 until the lever 26 has been moved to axial alignment with the rocker arm, whereupon the spring 23 operates to 80 impulsively actuate the rocker arm back to its full line position.

The switch may be mounted on any article or instrument which it is intended to control and for this purpose I have provided 85 apertures 32 in the end portion of the face plate 10. The apertures 32 are suitable for receiving screws, (not shown). The screws will serve to fasten the device to a plate member 33 or the like shown in dotted lines. 90 The member 33 may be any suitable portion of the device or instrument to which the switch is attached. An aperture 20 formed in the lower portion of the insulating sheets 12 is for convenience in inserting 95 a screw through the adjacent apertures 32.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned. 100

What I claim as new and desire to secure by Letters Patent is:

1. An electric switch comprising a plurality of contact brushes, a pivotally mounted rocker arm having an electrical connector ring mounted thereon, an operating lever having a socket formed therein and separate from said arm, said lever being pivotally mounted on an axis coincident with the pivotal axis of the arm and operatively related thereto, and resilient means having one of its end portions positioned in said socket and its opposite end engaging said rocker arm for imparting an impulsive movement to the arm and connector in a manner to connect or disconnect said brushes when said lever is moved in one direction or another. 115

2. An electric switch comprising a plurality of contact brushes, a pivotally mounted operating lever having a socket formed therein, a rocker arm independent of said lever and pivotally mounted on an axis coincident with the pivotal axis of the lever, an electrical connector ring surrounding the free end of said arm, and resilient means 125

operatively related to said socket and arm for imparting an impulsive movement to said arm and electrical connector in a manner to connect or disconnect said brushes when said lever is moved in one direction or another.

3. An electric switch comprising a plurality of contact brushes, a pivotally mounted operating lever having a socket formed therein, a rocker arm independent of said lever and pivotally mounted on an axis coincident with the pivotal axis of the lever, a plurality of insulating washers mounted on the free end of said arm and having shou-
10 dered portions formed on their adjacent ends,

15

an electrical connector ring mounted on said washers between said shouldered portions, a rivet for securing said washers to said rocker arm, and resilient means having one of its end portions engageable with said socket and its opposite end with said rivet for imparting an impulsive movement to said arm and electrical connector in a manner to connect or disconnect said brushes when said lever is moved in one direction or another.

70
75
In witness whereof, he hereunto subscribes his name this 30th day of January A. D., 1929.

THOMAS L. PARKER.
